TRACK SHORT-CIRCUITING DEVICE

James C. Mock, Detroit, Mich.

Application January 15, 1947, Serial No. 722,243.

1 Claim. (Cl. 246—34)

1

The present invention relates to railway track circuit shunt measuring means, and has among its objects the provision of a device for quickly and easily shunting and measuring such circuits.

In the modern railway signaling system, the rails of the track are bonded together to form electric conductors to carry currents which through suitable apparatus and appliances actuate the signals of the system. When such track circuits become broken through accident, or weakened by leakage, or affected by foreign currents, it becomes highly important to locate and repair such circuits. Even when in apparently good condition, frequent checking must be made to forestall failures in the signal system.

One of the checking operations is to shunt the circuit between the two rails of the track and also by means of a suitable meter inserted in the shunting device to measure the flow or lack of flow of current in the rails.

The present invention relates to means for making such intrarail circuit checks, and an object of the invention is to provide such a device that will make positive contact with the rails with a minimum of effort.

Another object is a device that may be quickly and easily put in place or removed and the check made by a single operator.

Another object is a device that has automatic adjustments for variations of gauge and sizes of rails.

Another object is a device of the kind indicated which may be used by trainmen to set a "stop" signal in an emergency.

Still other objects will readily occur to those skilled in the art upon reference to the following description and the accompanying drawings in which

Fig. 1 is a view, more or less diagrammatic, showing the method of use of the device.

Fig. 2 is a central longitudinal sectional view of the mid portion of the device.

Fig. 3 is a similar sectional view of one of the rail contacting ends.

Fig. 4 is a section on line 4—4 of Fig. 2.

Fig. 5 is a view similar to Fig. 1, but showing a modification.

Fig. 6 is a vertical longitudinal section of one end of the device of Fig. 5.

Fig. 7 is a plan view of the same.

Fig. 8 is a section on line 8—8 of Fig. 7.

As indicated in the drawings, the device comprises two, preferably tubular members 10 and 10A, hinged together as at 11 and so arranged that when the hinge is opened, the two members

2

will move beyond the position in which their axes are in alignment or the point at which the hinge pintle is in alignment with the ends—in other words, the hinged joint is a toggle.

Of the two members 10 and 10A, one or both of them will be provided with means for electrically insulating the one from the other. Such a construction is shown in Fig. 2, showing the member 10 as stopping short of the hinge 11 and to be provided with a short extension in the form of a plug 12 of suitable insulating material, such as fiber, or the like, having a reduced portion 12A extending into and fixed to tube 10 as by the bolt or screw 14. At its other end, the plug 12 is shown as having a reduced portion 12B surrounded by a metal sleeve 15 which may be fixed on the part 12 by the screws 11A serving to hold the hinge 11. Other screws 11B fix the other leaf of the hinge to the member 10A.

The screw 14 is preferably a through bolt or screw fixed by a nut 14A and having sufficient length to receive a thumb nut 14B and serve as a binding post 14C.

The free ends of members 10 and 10A are provided with means for establishing a good contact with the rails 15 and such means is shown in Fig. 3 as comprising what is known as an "automatic center punch" mounted in the end of the tubular member 10A, being slidable as a unit against a resilient backing element such as the spring 16 and held in place by a flanged nut 16A.

The automatic center punch comprises as is well known, a tubular housing 20 enclosing a spring 20A and plunger 20B and provided with an internal shoulder 21. The plunger 20B carries a laterally movable plug 22 through which is an opening 22A held normally in an eccentric position by a spring 22B, with its end extending laterally from the plunger in position to be moved by a shoulder 21 and to thereby center the opening 22A.

In the open end of housing 20 is fixed a hollow plug 23 through which extends axially a plunger 24 provided with a flange or shoulder 24A serving as an abutment for a spring 25. The other end of spring 25 abuts against the closure member or plug 23.

The plunger 24 has its projecting end sharpened as shown and extends through plug 23 and into plunger 20B to contact plug 22. When the plunger 24 is pressed against a surface, it moves inwardly, compressing first the lighter spring 25 and, through the coaction of plunger 24 and plug 23, then compressing spring 20A. When plug

22 reaches the shoulder 21, it is moved inwardly and thereby centers the opening 22A so that this end of plunger 24 may pass through plug 22 and into the short axial opening of the plunger 20B. When this happens, the plunger 20B is released and, driven by spring 20A, strikes a considerable blow against the inner end of plunger 24, driving the point against and into the surface against which it is pressed.

Each of the members 10 and 10A may be so 10 equipped.

Instead of the "punch" ends as described, it is also contemplated to use a rail contact maker such as is shown in Figs. 5 to 8. In these figures, the hinged members 110 and 110A will be substantially the same as members 10 and 10A, but instead of the "punch," will carry heads designated as a whole by the numeral 40.

Each of the heads 40 will consist of a rod 41 suitably fixed in the end of a member 10 or 10A and projecting therefrom. The rod 41 is provided intermediate its ends with a shoulder 41A or enlargement fitting slidably in a casing 42 enclosing a suitable spring 43.

The spring 43 surrounds the outer end portion of rod 41 and is designed to act between shoulder 41A and a cap 44 closing the outer end of casing 42. The rear end of casing 42 will also be closed by a cap 45 provided with a suitable opening for rod 41.

The cap 44, as shown, is threaded on the casing and is provided with an internal shoulder 44A adapted to coat with spring 43 and is lengthened axially and tapered, the outer surface of the taper being corrugated peripherally with the ridges 44B quite sharp. Further, the extreme end of the cap is sharply pointed as at 44C and a recess 44D provided for the reception of the end of rod 41.

Either form of the device may also be provided with means for aiding in the initial placing of the shunt means and for insuring the location of the points up under the rail head.

Such means consists of a flat spring 50 fixed to member 10 (or 10A) as by bolts 50A and extending over the contact head, being spaced somewhat therefrom. The spring 50 is preferably reinforced by a stirrup 51 and second spring 52, the stirrup 51 being fixed to the head 40 and

5 over the spring 50, while the spring 52 is fixed by bolts 50A and also extends under the stirrup 51. This second spring 52 has its outer end bent downwardly as at 52A to provide a hump 52B normally back of the stirrup, but, when the head 40 is moved backward, the hump 52B coacts with the stirrup 51 to increase the pressure of spring 52 on spring 50 and thereby the pressure of spring 50 on the rail.

15 In making tests of the rail circuits, a suitable meter 59 will be inserted in the rail to rail circuit by fixing a lead 60 to binding post 14C and another lead 61 fixed to a suitable screw 62 fixed in member 10A or 110A. When no test is desired but short circuiting of the rails is necessary, a conductor without the meter may extend from post 14C to screw 62.

I claim:

20 A railway track circuit shunt device comprising a pair of conducting members each having at one end means for making an electric contact with a rail, a hinge connecting the two members, means for insulating the one member from the other, and means for attaching a separate conductor to connect the two members, the combined length of said members and contact means being sufficient to extend from one rail to the other, said contact means including a prick punch and automatic means for delivering a hammer blow 25 to said punch.

30 JAMES C. MOCK.
